UNITED STATES PATENT OFFICE.

ELMER S. SHIMER, OF MILTON, PENNSYLVANIA, ASSIGNOR TO SAMUEL J. SHIMER & SONS, OF MILTON, PENNSYLVANIA, A CORPORATION.

CUTTER-HEAD.

1,143,449.

Specification of Letters Patent.

Patented June 15, 1915.

Application filed October 18, 1911, Serial No. 655,329. Renewed May 7, 1915. Serial No. 26,656.

To all whom it may concern:

Be it known that I, ELMER S. SHIMER, a citizen of the United States, residing at Milton, in the county of Northumberland and 5 State of Pennsylvania, have invented certain new and useful Improvements in Cutter-Heads, of which the following is a specification.

My invention relates to an improvement 10 in cutter-heads, and the object is to provide an assemblage of parts whereby the cutting knife and holding devices shall be held rigidly and in compact arrangement, thereby permitting the use of a large number of 15 holding devices in a single cutter-head flange when desired by the trade.

With the foregoing object in view, this invention comprises a cutter-head flange having the required number of bit-seats cut 20 transversely in the flange, in connection with knives or bits held tangentially in said seats, and a clamping block, one side of which is adapted to engage a knife or bit, and the other with the adjacent wall of the bit seat 25 having a transversely disposed tapering orifice formed partly in the block and in the opposite wall of the bit seat, a tapering bolt fitted to said tapering orifice and keyed to the cutter head flange in a manner to permit 30 it to move endwise, but preclude its turning, and a nut adapted to turn on the bolt to tighten the same in the orifice and clamp the bit or knife in its seat.

My present invention further consists in 35 certain novel features of construction and combinations of parts which will be hereinafter described and pointed out in the claim.

In the accompanying drawings:—Figure 40 1 is a bottom plan view of the cutter-head, Fig. 2 is a top plan view, Fig. 3 is a horizontal section, Fig. 4 is a vertical section on the line 4—4 of Fig. 1, and Figs. 5, 6, and 7 are detail views of the knife or bit, the clamping 45 block, and the bolt respectively.

The numeral 1 represents the hub, and 2, the flange of a cutter-head. The flange is provided with one or more recesses constituting bit seats 3, 3, and the rear edge of 50 said bit seats are disposed approximately

tangentially to the hub, and a portion of said walls are transversely corrugated as at 4.

The knife or bit 5 is provided with corrugations 6 on one side to fit the corrugations 4 on the rear wall of the bit seat. These corrugations on the knife and rear wall of the bit seat have the double function of assisting in holding the knife or bit and also in gaging and truing it in the assemblage and the adjustment of the parts. The outer working end of the knife or bit is sharpened and fashioned to make the desired cut.

A clamping block 7 having its opposite 65 sides parallel is inserted in the space between the knife or bit and the forward wall of the bit seat, these blocks being less in width than the space and adapted to fit snugly against the adjacent surface of the 70 knife or bit. A semi-circular opening or orifice is formed on a taper in each clamping block and opposite wall.

A bolt 8, one end of which is screw-threaded, and the main portion of which is 75 in the form of a taper to correspond with the orifices formed partly in the clamping-block and partly in the opposite wall of the bit seat, is provided with a key-way 9 adapted to receive a lug 10 in the portion of the 80 orifice in the flange to permit the bolt to move endwise and prevent its turning axially, and a nut 11 having a shoulder or collar 12 on one side screws on the thread of the bolt, and, when tightened, the collar 85 or shoulder bears on the flange or clamping block to tighten the parts and hold them rigidly in place. When the parts thus described are put into position, and the nut is drawn tight, the effect upon the block is 90 that it is pressed up against the round collar of the nut, but by continuing to turn the nut, the clamping block will again retreat to its position until the collar of the nut has its bearing against the side of the 95 solid semi-circular orifice, which lines up the parts. As the nut is drawn up, and the taper bolt is drawn into its two semi-circular openings, the space between the clamping block and the adjacent wall of the bit 100

seat is broadened and the parts described become very firmly and rigidly fixed.

While in the drawings the knife and knife-seat are shown corrugated, in practice this may not be essential, the object being to firmly hold the knife on the taper bolt and wedge in the manner described.

Referring again to the clamping block, it will be observed that it has a projection at 13 adjacent to the knife or bit, which serves to turn the chip, and may be termed a "chip-breaker."

It is clear that the knife or bit and clamping block correspond in width to that of the flange, so that their outer surfaces are flush with the opposite surface of the flange when held in place. It will also be understood that the knife or bit is capable of being adjusted in and out to suit the requirements, and the parts may be easily assembled or separated, and when in place are quickly fastened and held rigidly against accidental displacement.

It is evident that any number of knives or bits may be used. The ordinary feeding machine may require but two knives, whereas for special heavy duty eight, twelve, or as high as sixteen may be needed, the knife and its holding devices being so compact as to permit of a large number being used in a single cutter-head flange without diffi-

culty or at the expense of weakening any part.

Having fully described my invention, what I claim as new and desire to secure by Letters Patent, is:—

The combination with a cutter-head flange having a bit-seat cut in its periphery, one side of which is constructed and adapted to receive a bit, and the opposite side having a tapering groove, of a knife or bit engaging said first-mentioned side, a clamping-block fashioned to engage the knife or bit on one side and having a tapering groove on the opposite side in position to register with the groove of the bit-seat, and provided on the outer edge with a chip-breaker, and a bolt having a tapering portion which enters the tapering groove of the bit-seat and clamping-block, means to prevent the bolt from turning, and means for drawing the bolt endwise to force the clamping block rigidly against the knife or bit whereby to hold the latter securely between it and the opposite wall of the bit-seat.

In testimony whereof I affix my signature, in the presence of two witnesses.

ELMER S. SHIMER.
